Primary Examiner — Omeed Agilee(74) *Attorney, Agent, or Firm* — Fitch, Even, Tabin & Flannery LLP(57) **CLAIM**

The ornamental design for a medical procedure tray, as shown and described.

DESCRIPTION

FIG. 1 is a top perspective view of a medical procedure tray according to our new design;

FIG. 2 is a top perspective exploded view of the medical procedure tray according to FIG. 1 showing a basin and lid removed from the tray;

FIG. 3 is a top plan view of the medical procedure tray according to FIG. 1 with basin and lid removed;

FIG. 4 is a left side elevation view thereof;

FIG. 5 is a front elevation view thereof;

FIG. 6 is a right side elevation view thereof;

FIG. 7 is a rear elevation view thereof; and,

FIG. 8 is a bottom plan view thereof.
